UNITED STATES PATENT OFFICE.

FRANK OSCAR KNUUSI, OF HURON MOUNTAIN, MICHIGAN.

PROTRACTOR.

1,416,357.

Specification of Letters Patent. Patented May 16, 1922.

Application filed May 20, 1920. Serial No. 382,774.

To all whom it may concern:

Be it known that I, FRANK OSCAR KNUUSI, a citizen of the United States, residing at Huron Mountain, in the county of Marquette 5 and State of Michigan, have invented a certain new and useful Improvement in Protractors, of which the following is a specification.

This invention is a protractor device 10 adapted to many uses, but especially designed for use by carpenters and builders in marking boards or other timbers preparatory to cutting them to conform to irregular surfaces such for instance as the walls of a 15 log house against which it is desired they shall fit.

The object of the invention is to provide a device of this character with which an operator can by laying the board which is 20 to be cut against the wall which it is to fit, and running the device of this invention over it so mark the board that it can be cut to accurately fit the wall.

The invention consists in means for carrying out the foregoing objects which can be 25 easily and cheaply made, which is efficient in use, and is not readily liable to get out of order. More particularly the invention consists in features and details of construction 30 more fully set forth in the specification and claims.

Referring to the drawings in which similar numerals represent the same parts throughout the several views.

Figure 1 is a perspective view showing the board and the log wall to which it is to be applied and the mechanism of this invention in operative relation thereto.

Figure 2 is a sectional end view of the 40 pencil holder mechanism.

Figure 1 shows two logs 10 and 12 of an imaginary log building wall to which it is desired to tightly fit a board 14 preparatory to building a board wall at right angles to the log wall. The tool provided by this invention for properly marking the board happens to be applied to a carpenter's tri-square having the usual graduated long arm 16 and short arm 18, but the tri-square as 45 such forms no real part of this invention. The main thing about the tri-square is that its long arm 16 is provided with a transverse flange 20 which bears against the straight edge of the board 14 to guide the 50 tri-square up and down that edge of the board and that the short arm 18 of the tri-

square is provided with a longitudinal slot 22 which guides the sliding rod 24 as it moves in and out perpendicular to the edge of the board 14 and the long arm 16 of the tri-square. For purposes of giving this sliding bar 24 additional support the short arm 18 of the tri-square is provided with a supplemental rearwardly extending arm 26 sustained from the long arm 16 of the tri-square 60 by a diagonal brace 28.

The sliding rod 24 is provided at its end toward the log wall, hereafter referred to as the working end, with a point 30, preferably tapered to sufficient thinness so that when 70 in the full line position of Figure 1 it will enter between the logs 10 and 12 to as great a distance as it can possibly be hoped that a portion of the board 14 can be made to enter. Along the rod 24 at suitably short 75 intervals are a series of perforations 32 adapted to be entered by a suitable pencil 34. In the particular case here illustrated this pencil is detachably insertable in the pencil holder 36 which has on its lower end 80 a projecting lug 38 detachably fitting in perforations 32 in rod 24. This structure is such that any part of rod 24 which carries the pencil 34 may travel back through arm 18 as is necessary in tracing those parts of 85 lines 40 and 42 which lie to the left of the end of said arm 18, without being in any way stopped by the presence of the pencil. The pencil 34 may, if desired, be detachably secured in the pencil holder by set screw 40. 90

In the operation of the device the operator after first placing the board 14 against the logs as shown places the instrument with the tri-square and the rod 28 in the position shown in full lines in the drawing so that with the flange 20 bearing on edge 21 of the board the point 30 of the rod 24 is as far as it will conveniently go between the two adjacent logs 12 and 14 of the whole wall which has the deepest notch or recess between them. In this position the operator adjusts the pencil holder in the hole 32 which is opposite or nearest opposite the left hand edge 46 of board 14. He then moves the tri-square along edge 21 of the board 14 in the direction in which marking is to be done, holding the flange 20 of the tri-square solidly against the board as the tri-square moves. As the rod 24 was at the start way in between the logs it is impossible to carry out 105 this movement of the tri-square described without the operator taking hold of the 110

pencil at the handle and moving the rod 24 outward so that it at least no more than touches the log. By holding the point 30 of the rod 24 in contact with the adjacent 5 circumference of the log, as the tri-square is moved the pencil point will trace on the board 14 a line corresponding to the exact shape of the log which is followed. In the drawing the device is supposed to have 10 traced the line 40 corresponding to the semi-circumference of log 10 before reaching the point shown in full lines from which it is about to trace line 42, corresponding to the semi-circumference of the log 12. The dotted line portion of Figure 1 shows the position 15 of the point 30 of the rod 24 and the short arm 18 of the tri-square when the device has moved down sufficiently to be marking line 42 at a point approximately opposite the center of the log 12.

After the board 14 is marked with lines 20 40 and 42 corresponding to the respective logs, proper tools can be used to cut away the board portions to the right of these lines 25 40 and 42 whereupon the surface edge of the board adjacent to the wall will be exactly the proper shape to accurately fit each log of the wall.

By rigidly securing rod 24 in one position 30 in the tri-square, as for instance by the use of a set screw 47, the device may be used to cause the pencil 34 to mark a straight line on the board 14 parallel to the side of the board which is engaged by the flange 20 35 while the tri-square is moved down the board. This is of use in marking the board for straight ripping in the ordinary manner.

By removing the rod 24 from the tri-square and pivoting it at any one of the 40 holes 32 which may be selected, the device may be used as a compass for drawing circles around the particular point selected.

It will be observed that when I specify in the claims a pencil device carried by and 45 movable with the rod to effective marking positions within the marginal limits of the member, such expression shall be construed as meaning that the pencil 34 is movable to effective marking positions disposed entirely 50 between all marginal edges of the member or arm which carries the pencil supporting rod 24.

Having thus described my invention what

I claim as new and desire to secure by Letters Patent, is:—

1. In mechanism of the class described, a member adapted for movement along the edge of an article to be marked, a rod slidably mounted on the member for movement at an angle to the direction of operative movement of the member, and a pencil device carried by and movable with the rod to effective marking positions within the marginal limits of the member.

2. In mechanism of the class described, a 65 guide member adapted to travel along the edge of a board to be marked, a rod slidable in the guide member at an angle to the direction of operative movement of the member, and a pencil device carried by the rod and 70 adjustable with respect thereto to effective marking positions within the marginal limits of the guide member.

3. In mechanism of the class described, a 75 tri-square, having on one arm a flange for engagement with the edge of a board, a rod slidably supported by the other arm of the tri-square for movement at an angle to the first arm, and a pencil device adjustably carried by the rod and movable with the latter 80 to effective marking positions within the marginal limits of the second arm.

4. In mechanism of the class described, a 85 tri-square having a relatively long arm with a projecting flange thereon, another arm extending across the end of the first arm and on both sides thereof, means for bracing one end of the second arm from the first arm, a rod slidably in and guided by the second arm at right angles to the first, and having 90 a point, there being in said rod along its length a series of perforations for the reception of a pencil point, and a pencil holder adapted to be detachably inserted in a selected one of said holes, so that the point of 95 the pencil inserted therein will pass through said rod and mark on a surface below said rod, all the parts being arranged, shown and described for the purposes set forth.

In witness whereof, I have hereunto subscribed my name in the presence of two witnesses.

FRANK OSCAR KNUUSI.
